DOORKNOB STRUCTURE

Walter R. Schlage, deceased, late of Burlingame, Calif., by Anna Schlage, executrix, Burlingame, Calif., assignor to Schlage Lock Company, San Francisco, Calif., a corporation of California

Application December 14, 1946, Serial No. 716,307

10 Claims. (Cl. 292—347)

1

This invention relates to a knob structure particularly intended for use as a door knob, the present device being a modification of and improvement on the showing in Patent No. 2,294,213 issued August 25, 1942, and entitled "Door Knob Structure."

The knob structure disclosed in the above patent is made from sheet metal by die-forming operations and comprises three main parts; to wit, an outer shell, an inner shell, and an elongated cylindrical shaped shank. The inner shell is first secured to the inner end of the shank by means of bendable lugs, and then the outer shell is telescoped over the inner shell and a portion of the outer shell is spun over the inner shell permanently to secure the shells together. Such a structure does not have sufficient rigidity and strength for all installations. Instances have been encountered where the knob has been bent with relation to the shank or the securing lugs have broken.

The object of the present invention is generally to improve and simplify the construction and operation of knob structures; to provide a sturdy and firm knob structure comprising an inner shank, an outer shell, and an inner shell; and particularly, to provide means for securing inner and outer shells and a shank in such a manner that the strength and rigidity required for all installations are provided.

The knob structure is shown by way of illustration in the accompanying drawings in which:

Figure 1 is a vertical longitudinal section of a closed end knob showing it applied to a door lock spindle;

Figure 2 is a perspective view of a partly formed outer shell of the knob;

Figure 3 is a perspective view of a partly formed inner shell of the knob;

Figure 4 is a perspective view of a tubular shank;

Figure 5 is a perspective view of a knob section;

Figure 6 is a perspective view of a door lock spindle;

Figure 7 is a section similar to Figure 1 but showing an open end knob.

The door knob structure includes an outer hollow shell A, an inner hollow shell B, a tubular shank C, and a knob section D. Each of the shells A and B is formed from sheet metal by die-punching operations and when ready for assembly, has an intermediate shape as shown in Figure 2 or 3. The inner shell B has an approximately radial end wall 2 pierced by a series of radially disposed slots 3 or perforations. Also,

2

the radial wall 2 has a central boss 2a protruding therefrom. The tubular shank C has a series of lugs 4 formed at one end in position to enter the slots 3 of the inner shell. When the lugs are fully inserted and the outer end 5 of the tubular shank engages the radial end wall 2 of the shell, the lugs are then bent over, as shown in Figure 1 to secure the inner shell to the outer end of the shank. The partially formed outer shell A is then telescoped over the inner shell and the outer and inner shells are united by spinning or pressing the central and inner portions 7 thereof inwardly toward the shank C thereby forming a hollow, rounded hand grip secured to the outer end of the shank C by the lugs 4.

The tubular shank may be formed from tubing or from flat sheet metal rolled or formed into a partial tube. In either case a slot 8 is formed throughout its length and a key 9 is also formed in it by forcing a portion of the metal inwardly. A pair of apertures 10 are cut in the shank opposite each other to receive an assembly latch hereinafter to be described.

A door knob spindle E employed with this knob is tubular in cross section and of an exterior diameter such that the shank C will telescope over it and fit it snugly. A radially extending rollback 11 formed on the inner end of the spindle E actuates a lock rollback member (not shown). The spindle E is provided with a slot 21 functioning as a key-way in conjunction with the key 9 formed in the shank C.

In order that the knob structure may be secured against inadvertant removal from the spindle E, a spring actuated latch 12 is employed. This latch is a small, approximately rectangular plate perforated to receive one end of a spring 13, secured to the spindle in any suitable manner. When the knob structure is applied by telescoping the shank C over the spindle E with the key 9 in the slot 21, the latch 12 is manually depressed. When the knob structure is pressed inwardly and finally reaches the proper position on the spindle, the released latch 12 registers with one of the apertures 10 and springs outwardly to project into the aperture and thereby secures the knob structure on the spindle against accidental endwise removal.

The grip or hand portion of the knob structure is not only secured to the outer end of the shank C by means of the bendable lugs 4, but is also supported with relation of the inner end of the shank. This is accomplished by the knob section D. A somewhat conical portion 14 is formed 55 from sheet metal by die-forming operations and

is provided with a flange 15 at the large end. The flange is turned in to secure a radial reinforcing washer 16 or annular disc. An opening 17 in the washer snugly engages the exterior surface of the shank C. The conical portion 14 has an in-turned flange engaging the end of the shank C and has an inturned tongue 18 at its inner end to function as a key member in the slot 8 of the shank C, thus securing the knob section D against rotation with relation with the shank or the inner and outer shells A and B. The flange 15 fits the opening 19 defined when the inner and outer shells are spun or pressed into their final shape to form a support for the inner end of the shells A and B. This inter-engagement prevents bending of the inner and outer shells with relation to the shank C or the spindle E upon which it is mounted. The shells A and B are supported at both the outer end and the inner end and adequate strength and rigidity are thus provided.

A small hole 20 is formed in the knob section 14 to align with the active one of the slots 18 of the shank. A nail or similar tool can be inserted through the hole 20 and the latch 12 may be so engaged and depressed when it is desired to remove the knob structure from the spindle.

The radial wall 2 of the inner shell B supports the hand grip part of the knob structure with relation to the outer end of the shank C and the conical knob section D including the washer 16 supports the hand grip part of the knob with relation to the inner end of the shank. The central boss or protrusion 2a on the inner shell supports the end of the outer shell, thus adding axial rigidity to the knob structure.

In some instances, a central opening 25 is formed in the outer shell A (see Fig. 7). The boss or protrusion 2a is then omitted or punched out to leave an opening 24 in the inner shell in alignment with the opening 25. The openings 24 and 25 are provided for the insertion of a push button actuated mechanism or for the insertion of a key-actuated locking mechanism. Even with the openings 24 and 25, the outer shell A is still supported as the opening 25 is rimmed by an annular flange 24a which rests on the surface of the radial plate 2 of the inner shell B.

In the construction described in the foregoing description, the inner and outer shell sections A and B are supported with relation to the inner and outer ends of the shank C, and great strength and rigidity are obtained. While this and other features of the invention have been more or less specifically described and illustrated, it should be understood that changes may be resorted to within the scope of the appended claims.

Having thus described the invention, what is claimed and desired to be secured by Letters Patent is:

1. A door knob structure comprising a hollow shell closed at one end and open at the opposite end, a tubular shank extending through the open end of the shell, means securing the closed end of the shell to one end of the shank both against rotation and endwise movement with relation to the shank, a knob section telescoping over said shank and engaging said shell, and an annular disc in said knob section engaging said shank.

2. A door knob structure comprising a hollow shell at one end thereof having an end wall and at the other end thereof having an opening, there being a plurality of perforations formed in the end wall, a tubular shank extending through said opening, and a series of lugs on one end of the

shank extending through said perforations and bent over to secure the tubular shank to the hollow shell.

3. A door knob structure comprising an inner shell, an outer shell telescoping over and enclosing the inner shell said inner shell at one end thereof having an end wall having a series of slots formed therein, the other end of the inner shell and of the outer shell having an opening, a tubular shank extending through said opening, a series of lugs on one end of said shank extending through said slots and bent over to secure the inner shell to the shank, and a knob section carried by the opposite end of the shank, said knob section forming a closure for said opening and supporting said other end of the inner and outer shells with relation to said opposite end of the shank.

4. A door knob structure comprising a shell having a small opening in one end and a larger opening at the opposite end, a tubular shank extending through the larger opening and at one end into contact with said one end of the shell and in alignment with the small opening, means securing the shell to said one end of the shank, and means adjacent the other end of the shank to support the opposite end of the shell.

5. A door knob structure comprising a hollow shell closed at one end and open at the opposite end, a tubular shank extending through the open end of the shell and engaging the closed end of the shell, said shank having a key way formed therein, means securing the closed end of the shell to one end of the shank both against rotation and endwise movement with relation to the shank, a knob section telescoping over the opposite end of the shank, an annular flange on said knob section extending into and closing the open end of the shell, and a key member on the knob section engaging the key way in the shank to secure the knob section against rotation with relation to the shell and the shank.

6. A door knob structure comprising a hollow shell closed at one end and open at the opposite end, a tubular shank extending through the open end of the shell and engaging the closed end of the shell, means securing the closed end of the shell to one end of the shank both against rotation and endwise movement with relation to the shank, a knob section telescoping over the opposite end of the shank, an annular flange on said knob section extending into and closing the open end of the shell, and a reenforcing washer secured in the knob section, and engaging the shank.

7. A door knob structure comprising a hollow shell closed at one end and open at the opposite end, a tubular shank extending through the open end of the shell and engaging the closed end of the shell, means securing the closed end of the shell to one end of the shank both against rotation and endwise movement with relation to the shank, a knob section telescoping over the opposite end of the shank, an annular flange on said knob section extending into and closing the open end of the shell, a reenforcing washer secured in the knob section, and engaging the shank and an inturned flange on the knob section engaging an end of the shank.

8. A door knob structure comprising a hollow shell having an end wall at one end thereof and having an opening at the other end thereof, there being a plurality of perforations formed in the end wall, a tubular shank extending through said opening, a series of lugs on one end of the shank

extending through said perforations and bent over to secure the tubular shank to the hollow shell, and means on the opposite end of the shank forming a closure and a support for said other end of the hollow shell.

9. A door knob structure comprising a hollow shell having an end wall at one end thereof and having an opening at the other end thereof, there being a plurality of perforations formed in the end wall, a tubular shank extending through said opening, a series of lugs on one end of the shank extending through said perforations and bent over to secure the tubular shank to the hollow shell, and a knob section carried by the opposite end of the shank, said knob section forming a closure for said other end of the hollow shell and also supporting said other end of the hollow shell with relation to the shank.

10. A door knob structure comprising a tubu-

lar shank, an inner shell having a wall mounted on and extending radially from one end of said shank, a support mounted on and extending radially from an intermediate portion of said shank, and an outer shell encompassing said inner shell and said support and supported thereon.
